UNITED STATES PATENT OFFICE.

ALEXANDER M. HUDSON, OF NEW YORK, N. Y.

INDICATOR FOR MOTOR-CARRIAGES.

No. 910,287.

Specification of Letters Patent.

Patented Jan. 19, 1909.

Application filed December 6, 1907. Serial No. 405,404.

To all whom it may concern:

Be it known that I, ALEXANDER M. HUDSON, citizen of the United States, residing at New York, in the county of New York and State of New York, have invented certain new and useful Improvements in Indicators for Motor-Carriages, of which the following is a specification.

My invention relates to indicators for motor carriages, and has for its object the construction of various related devices having particular construction and special arrangement whereby there may be set forth alternately upon a single dial by the agency of a single battery and a single electro-magnet, the speed at which the vehicle is moving at any time, and the amount of fuel, water, or lubricating oil contained in the receptacles for them.

I accomplish the stated object by fashioning and associating the different elements substantially as illustrated in the accompanying drawings, of which—

Figure 1 represents a face view of the indicator dial and box with portions broken away to disclose internal parts. Fig. 2 is a vertical section upon the line X—X of Fig. 1. Fig. 3 is a plan view of the circular armature, showing the roughened or knurled face. Fig. 4 is a top view of the electro-magnet showing the non-magnetic pole guards which are also roughened.

Like reference numbers are employed throughout to refer to the same parts.

Considering the drawings, it will be noted that the box 1 has arranged at the upper part a dial 2. A hand 3 is arranged to sweep the dial, and the extremity of the hand comes into contact with one after another of the insulated contacts 4 borne by the dial.

At the lower portion of the front of the box are shown four pedals 5. Each pedal has a recess 6 in its center or hub, and a pin 7 projects from the rock shaft 8 through each recess 6. Thus, either pedal may be operated on rocking shaft 8 without disturbing the remaining pedals. Secured upon the rocking shaft is a relatively larger grooved pulley 9, and a wire cord 10 connects it with the relatively smaller grooved pulley 11 shown in Fig. 2. Pulley 11 is constructed of one piece with a disk 12, and a spiral spring 13 connects that disk with the hand 3. The hand 3 is not otherwise connected with the disk or smaller pulley, but

is free to move with the sleeve 14 to which it is attached. The smaller pulley 11 and the disk 12 rotate upon the sleeve 14. The circular armature 15 rotates with sleeve 14, and has a movement along the sleeve 14 when it is attracted towards the pole guards 16, and the coil spring 17 tends to keep the armature yieldingly away from the pole guards.

As shown in Figs. 3 and 4, the inner face of the circular armature and the faces of the pole guards 16 are roughened in some convenient manner. It is also to be understood that the pole guards 16 are of non-magnetic metal in order that there may be no sticking when the armature is released. To provide for the limited movement of the armature 15 along the sleeve 14, a pin 18 fixed in the sleeve 14 engages a slot 19 in the center or hub of the armature. Thus, the magnet 20 when energized draws the armature into contact with the pole guards, and when a circuit is broken, the spring 17 moves the armature from the magnet. The dial may be lighted at night by a suitably arranged glow lamp 21. For the purpose of ascertaining the speed, a governor 22 is employed, driven by the movement of the carriage, and attached to the brush 23. As the governor is operated it overcomes the tension, more or less, of springs 24, and the brush 23 moves along the commutator 25. The brush may be held against rotation by having its end in movable contact with the conducting bar 26 arranged opposite the commutator. The casing inclosing the governor is supported upon the driving shaft of the carriage and prevented from rotating by suitable connection with the frame 28 of the vehicle.

Fluid columns 29 of any desired size are each provided with a cord 30 which passes over a small pulley and has one end connected to the slide 31, which may rise and fall in metallic contact with the insulated rod 32. The brush 33 on the slide is thus brought into contact one after another with the insulated plates 34 arranged in succession upon the outside of the column. As the float rises or falls the slide is moved correspondingly. The slide is at the top of the rod 32 when the column is empty, and at the bottom of the rod when the column is filled with liquid.

Considering the lower portion of the box in Fig. 1, it will be observed that each

pedal 5 has attached to or formed integrally with its hub, a sleeve 36, movable with respect to the shaft 8, and at the end of each sleeve 36 is a disk 37. Now inspecting Fig. 5 2, it is seen that one side of the disk 37 is cut off upon the chord of an arc of the circle, and rests flatwise against the auxiliary spring 38, which in its turn lies against the conductor spring 39, although the two 10 springs are insulated one from the other. Spring 39 has its free end very near but not touching the insulated conducting strip 40. Current is supplied by a single battery 41 of suitable strength.

15 The spring 42 shown in Fig. 2 is introduced to return the hand into its normal attitude. The spring 42 is connected with the cord 43 which is attached to the grooved pulley 44. In Fig. 2 the hand is shown as 20 having been moved quarter way round the dial face, and the spring 42 is somewhat compressed. Its reaction draws upon the cord 43, turns pulley 44, and brings the hand 3 against its stop 45. Let it be assumed that the driver of the carriage seeks 25 to learn how much fuel oil he has remaining. He presses the pedal second from the right with his foot. He presses the pedal all the way down as far as it will go. By means 30 of pulley 9, cord 10, and pulley 11, the disk 12 is now turned and by reason of the connection through spiral spring 13 with the hand 3, the hand is also turned, but with a somewhat lagging movement at the 35 start, owing to the facts that it frictionally engages contact 4 and that the force of spring 42 must be overcome by the greater stiffness of spring 13. In other words, the spiral spring 13 must be of such strength as 40 to move the hand 3 promptly in spite of the friction with contacts 4 and the tension of the weaker spring 42.

In accordance with the arrangement of the parts of my invention illustrated herein, 45 when the hand reaches the contact 4 against which is the larger numeral 3, or any chosen mark, a circuit is completed from that contact by way of conductor 46 and its branch 47 to the fourth plate 34 from the top in the middle column which contains the fuel or 50 part thereof. Brush 33 of slide 31 lies in contact with that plate 34, and the current passes by way of conductor 49, conductor spring 39, and strip 40, through battery 41, and by way of the conductor 48 through 55 magnet 20, thence to the casing with which the conductor is joined, and, obviously, to hand 3 and the contact by reason of the metallic connection of the hand with the casing.

60 1. The circular armature is instantly attracted, and the roughened surfaces of the armature and the pole guards 16 engage. The armature cannot further rotate, nor can the sleeve 14, but the disk 12 may rotate further, with the result of additionally coiling spiral spring 13. In fact, the pedal being in every instance pressed entirely down, after the hand is magnetically halted the spring 13 is almost always additionally coiled as explained. Thus, while the hand 70 is moved by the operation of the pedal, the extent of its movement when the magnet is energized is independent of the extent of the movement of the pedal. As soon as the foot is taken from the pedal the combined forces of springs 38 and 39 acting below the center of disk 37 return the disk and pedal to their normal positions of rest and hold them there. It will be noted further that the contact between spring 39 and strip 40 80 occurs at the outset and continues as long as the pedal is held down. The contact occurs when the hand 3 touches the first of contacts 4. Next let the speed pedal be pressed and assume that the speed of the motor is such 85 that the brush 23 contacts with that bar of commutator 25 corresponding to sixteen miles speed in one hour. The circuit now is made from the contact 4 against which is the number 16, by way of conductor 46 to 90 commutator 25 by way of brush 23, bar 26, conducting spring 39, strip 40, through the battery and magnet to the casing as before explained, and the hand is magnetically stopped at the dial number 16. The reaction of spring 42 returns the hand when the 95 circuit is broken. A stop 50 on cord 43 limits the action of spring 42 and prevents the end of hand 3 from being thrown too violently against its own stop 45. While desirable, the stop 50 is not essential.

The central rod or bolt 51 supports the rotating sleeves and pulleys as shown in Fig. 2. Thus, it is believed to be now clear that the single battery and magnet are arranged 105 to operate the hand of the single dial to show the speed, or amounts of water, fuel and oil upon the same dial.

Having now described my invention and explained the mode of its operation, what I 110 claim is—

1. In an indicator, the combination with a dial provided with insulated contacts, of a hand arranged to sweep the dial and touch the contacts successively, a stationary magnet in circuit with the said hand and contacts, an armature for said magnet arranged to rotate with the said hand, and means including a spring and adapted to move the hand and armature, substantially as described.
2. In an indicator, the combination with a dial provided with insulated contacts, of a hand arranged to sweep the dial and touch the contacts successively, a commutator, a brush, devices constructed to move the brush in contact with the commutator, a stationary magnet, in circuit with the said hand and insulated contacts and with the said commutator, an armature for said mag- 130

let arranged to rotate with the said hand, and means including a spring and adapted to move the hand and armature, substantially as described.

3. In an indicator, the combination with a dial provided with insulated contacts, of a hand arranged to sweep the dial and touch the contacts successively, a circuit-breaking device, a stationary magnet in circuit with the said hand and insulated contacts and with the said circuit-breaking device, an armature for said magnet arranged to rotate with the said hand, and means including a spring and adapted to move the hand and armature, substantially as described.

4. In an indicator, the combination with a dial provided with insulated contacts, of a

hand arranged to sweep the dial and touch the contacts successively, a stationary magnet, an armature for said magnet arranged to rotate with the said hand, and means including a spring and a circuit-breaking device and adapted to move the hand and armature, the said magnet being in circuit with the hand and insulated contacts and with the said circuit-breaking device, substantially as described.

In testimony whereof I affix my signature in presence of two witnesses.

ALEXANDER M. HUDSON.
